No. 787,703.

PATENTED APR. 18, 1905.

L. O. SHERVEN.

DRAFT EQUALIZER.

APPLICATION FILED JULY 19, 1904.

UNITED STATES PATENT OFFICE.

LARS O. SHERVEN, OF MARSHALLTOWN, IOWA.

DRAFT-EQUALIZER.

SPECIFICATION forming part of Letters Patent No. 787,703, dated April 18, 1905.

Application filed July 19, 1904. Serial No. 217,184.

To all whom it may concern:

Be it known that I, LARS O. SHERVEN, a citizen of the United States, residing at Marshalltown, in the county of Marshall and State of 5 Iowa, have invented a certain new and useful Draft-Equalizer, of which the following is a specification.

The objects of my invention are to provide a draft-equalizer especially designed to be 10 applied to a running-gear of a wagon without the necessity of boring holes in the running-gear or permanently attaching any of the parts of the equalizer thereto.

A further object is to provide an equalizer 15 of this class to which one draft-animal may be attached on one side of the wagon-tongue and two draft-animals on the other side and the draft be applied to the running-gear in such a way as to prevent side draft upon the 20 tongue and to apply the draft to the front and back axles of the running-gear.

My invention consists in the construction of the draft-equalizer and in its arrangement and combination with a wagon, as hereinafter 25 more fully set forth, pointed out in my claims, and illustrated in the accompanying drawings, in which—

Figure 1 shows a top or plan view of the complete device applied to a wagon running-gear. The wagon-wheels are omitted. Fig. 2 shows a central longitudinal sectional view of same. Fig. 3 shows a detail perspective view of the device to be attached to the front end portion of the wagon running-gear, and 35 Fig. 4 shows a detail rear end view of the central portion of the bolster and axle of the rear portion of a wagon running-gear to illustrate the device for attaching a draft-rod to the rear end of the wagon.

Referring to the accompanying drawings, 40 I shall first describe those parts of the wagon running-gear to which my attachment is connected.

The numeral 10 indicates the front axle, 45 upon which the bolster 11 is mounted. A king-bolt 12 passes through the center of the axle and bolster, thus pivotally connecting them.

The numeral 13 indicates the wagon-reach, 50 the forward end of which is inserted between

the axle 10 and bolster 11 and is held in position by the bolt 12.

The numeral 15 indicates the front hounds of the wagon running-gear, to which the tongue 16 is pivoted by the bolt 17. 55

At the rear end of the wagon is the axle 18, upon which the bolster 19 is mounted. The rear end of the reach 13 passes between the rear axle and the rear bolster 19.

The parts just described constitute the running-gear of the ordinary wagon now in common use. 60

My attachment comprises an evener-bar 20, having attached to its outer end a swingletree 21. At a point two-thirds of the length of 65 the evener-bar from the end to which the swingletree 21 is attached I have provided a clevis 22, and the evener-bar is supported upon the tongue 16 of the wagon by means of a supporting-bar 23, one end of which is piv- 70 oted to the clevis 22 and the other end is connected by a bolt 24 to the wagon-tongue. This bolt 24 is passed through the wagon-tongue at the point where the opening is usually provided for attaching a doubletree and 75 is attached to the clevis 22 by a chain 22a. Hence it is not necessary in applying my draft-equalizer to the tongue to bore any openings not usually provided in a wagon-tongue. At the other end of the evener-bar 20 at a 80 point a slight distance beyond the tongue—that is to say, on the side opposite from the side where the swingletree 21 is placed—I have connected the doubletree 25 with the evener-bar 20. Attached to the doubletree 25 is a 85 swingletree 26 on the same side of the tongue as the swingletree 21, and on the other end of the doubletree 25 is a swingletree 27 on the opposite side of the tongue. In this way one draft-animal stands on one side of the tongue 90 and two draft-animals on the other side, and the draft is equalized at the clevis 22. In this connection it is to be understood that the supporting-bar 23 is not provided for the purpose of applying draft direct to the tongue, 95 but is simply for the purpose of supporting the evener-bar 20.

I have provided a bracket to be mounted on the front end of the reach 13 and held in place by the king-bolt 12. This bracket comprises 100

a flat bar 28, designed to rest against the under surface of the forward end of the reach. It is provided at its forward end with an opening 29 to receive the king-bolt 12, as shown in 5 Fig. 2. On top of its other end is an angular sleeve 30, through which the reach is passed to thereby retain the bar 30 in line with the reach. On the bottom of the rear end of the bar 28 is an extension 28^a, projected down- 10 wardly, then forwardly, and then upwardly to a point near the central portion of the bar 28, at which point it is attached by means of the rivets 31. Pivoted to the under surface of this downwardly-extending portion 28^a is a lever 32, connected to the downwardly-extended 15 portion by the pin 33.

The numeral 34 indicates a draft-rod attached at its forward end to the clevis 22 and at its rear end to the central portion of the 20 lever 32 by means of the pin 35. At the outer end of the lever 32 I have attached a draft-rod 36, and this draft-rod is extended rearwardly and attached to a bracket at the rear of the rear axle. This latter bracket comprises a block 25 37, through which the rear end of the rod 36 is passed, and said rod is held to the block by means of the nuts 38. The said block rests against the rear faces of the axle 18 and the bolster 19 and is held in position on the reach 30 33 by means of the metal loop 39, secured by the bolts 40 to the block 37.

In applying an improved draft-equalizer to the ordinary wagon running-gear I connect the supporting-bar 23 with the tongue by 35 means of the bolt 24, which bolt is passed through the opening ordinarily provided in a tongue for attaching a doubletree. I connect the evener-bar with the supporting-bar 23 by the chain 22^a and then connect the bar 28 40 with the front end of the reach by first removing the king-bolt 12, then passing the reach through the loop 30, and then placing the reach and the bar 28 between the axle 10 and the bolster 11, and then inserting the 45 king-bolt 12 through the reach and through the opening 29. I then place the block 37 against the rear of the axle 18 and bolster 19. The draft-rod 34 may then be connected with the lever 32 and the clevis 22, and the draft-rod 36 is then connected with the outer end 50 of the lever 32, passed between the axle 18 and the bolster 19, through the block 37, and the nuts 38 are then placed on its end. In this way all of the draft applied to the clevis 55 22 is transmitted to the lever 32. My object in having this lever some distance below the reach 13 is so that it will not interfere with the hounds of the wagon or with the front axle. The draft which is applied through 60 the draft-rod 34 to the lever is distributed upon the king-bolt 12 through the bar 28 and upon the block 37 through the draft-rod 36 because the draft-rod 34 is attached to the center of the said lever. The draft that is applied to the block 37 is transmitted to the 65

central portion of the rear axle 18 because the block 37 bears against it. In this way by distributing the draft to the front and rear axles the said axles are held exactly in line with each other when the vehicle is being advanced, for the action of the draft applied to the front axle will be the same as that applied to the rear axle.

Having thus described my invention, what I claim, and desire to secure by Letters Patent of the United States therefor, is—

1. The combination of a draft-equalizer, means for supporting it at its draft center upon the wagon-tongue, a draft-rod pivoted to the draft center of the draft-equalizer and extended rearwardly, a lever designed to be fulcrumed to the front portion of a wagon running-gear and having said draft-rod pivoted to its central portion, a second draft-rod pivoted to the outer end of said lever projected rearwardly and inwardly and means for connecting its rear end to the rear portion of a wagon running-gear.

2. The combination of a bar formed with a loop at one end and an opening at its other end, a lever pivoted to said bar, an evener-bar, a draft-rod attached to the evener-bar and to said lever and a second draft-rod attached to the lever and extended in a direction opposite from the first draft-rod.

3. The combination of a lever, an evener-bar, a draft-rod attached to the evener-bar and to said lever, a second draft-rod attached to the lever and a device shaped to receive the rear end of a wagon-reach and to engage the rear of a wagon-axle having said second draft-rod attached thereto.

4. The combination of a bar formed with a loop on one end and an opening at its other end, a downward extension on the end thereof having said loop, a lever pivoted to said downward extension, an evener-bar, a draft-rod attached to the evener-bar and to said lever and a second draft-rod attached to the lever and means for connecting it with the rear of a wagon.

5. The combination of an evener-bar, a lever designed to be attached to the front portion of a wagon, a draft-rod connecting the evener-bar and the lever, a second draft-rod attached to the lever and a device attached to the other end of the second draft-rod comprising a block having the draft-rod attached thereto and designed to rest against the rear axle of a wagon and a loop connected with the block shaped to encircle the rear end portion of a wagon-reach.

6. The combination of an evener-bar, a draft-rod connected with the evener-bar, a bar formed with a loop at its top on one end, an opening in its other end and a downward extension on the end having said loop, a lever pivoted to the downward extension, said draft-rod connected to the central portion of said lever, a second draft-rod attached to the outer 125 130

end of said lever, a block attached to the rear end of said second draft-rod and a loop connected with the block designed to encircle the reach of a wagon.

5 7. The combination with a wagon running-gear, of an evener-bar, a supporting-bar pivoted to the evener-bar and to the wagon-tongue, a bar formed with a loop at the top of one end a downward extension at the bottom of said end and an opening in the other end said loop designed to receive the wagon-reach and said opening designed to receive a king-bolt between the front axle and front bolster of the wagon, a lever pivoted to the under surface of the downward extension and projected laterally having said draft-rod connected to its central portion, a second draft-rod pivoted to the outer end of said lever and a block resting against the rear face of the rear

axle having, said draft-rod attached thereto, 20 and formed with a loop to encircle the rear end of the wagon-reach.

8. The combination of an evener-bar, a swingletree attached to one end, a doubletree attached to the other end, a clevis pivoted to 25 the evener-bar at a point adjacent to the end to which the doubletree is attached, draft devices connected to said clevis and a supporting-bar pivoted to the evener-bar at the point where the clevis is attached projecting toward 30 the end to which the doubletree is attached to support the evener-bar on a wagon-tongue with the tongue near the central portion of the doubletree.

LARS O. SHERVEN.
